CLAIM

The ornamental design for a reagent cartridge for colorimeter, as shown and described.

DESCRIPTION

FIG. 1 is a front perspective view from the left side of a reagent cartridge for colorimeter showing our new design; FIG. 2 is a rear perspective view thereof; and, FIG. 3 is a front perspective view thereof with the body of colorimeter illustrated in a removed condition.

The broken line showing of a colorimeter is for illustrative purposes only and forms no part of the claimed design.
